UNITED STATES PATENT OFFICE.

JOHN ROBINSON, OF PHILADELPHIA, PENNSYLVANIA, ASSIGNOR OF ONE-HALF TO WILLIAM J. CHANINEL, OF SAME PLACE.

MANUFACTURE OF ELECTRIC CONDUCTORS.

SPECIFICATION forming part of Letters Patent No. 529,413, dated November 20, 1894.

Application filed March 6, 1894. Serial No. 502,487. (No model.)

To all whom it may concern:

Be it known that I, JOHN ROBINSON, a citizen of the United States, residing at Philadelphia, in the county of Philadelphia and State 5 of Pennsylvania, have invented certain new and useful Improvements in the Manufacture of Electric Conductors, of which the following is a specification.

My invention has relation to the construction of electric conductors; and more particularly to the mode of and apparatus for insulating, covering and cording the same.

The principal objects of my invention are first, to provide a comparatively simple, economical and efficient mode of applying to a drawn rotatable wire fibrous material, such as cotton or the like, in such manner as to be wrapped and compacted thereto, then winding a cord or thread in uniform layers onto the covered wire to form a binder therefor and subsequently subjecting the same to a bath of insulating material in a molten or other state so as to thoroughly insulate the same and to constitute an electric conductor; second, to provide a continuous mode of insulating a wire while revolving under required tension and applying fibrous material in sheet or other form thereto and compacting the same thereon, then cording the surface of the covered wire and by a drawing action laying up the insulated fibrous covered and corded conductor for subsequent use; and third, to provide suitable apparatus for carrying into effect the mode of making an insulated electric conductor of my invention.

My invention stated in general terms, comprises the mode of making an electric conductor, by continuously drawing a rotated wire through a bath of insulating material, and while still moist, applying and compacting fibrous material, such as cotton or the like thereto, then cording the insulated and covered wire and laying up the same for subsequent treatment or use; and my invention further consists of apparatus for the conduct of the mode of making an electric conductor hereinafter described and claimed.

The nature and general features of my invention will be more fully understood from 50 the following description taken in connection

with the accompanying drawings forming part hereof; and in which—

Figures 1 and 2, represent partly in elevation and partly in section a plant adapted for the conduct of the mode of producing an insulated electric conductor of my invention. Fig. 3, is a perspective view of the laying up reel and cord and pulley mechanism for actuating the same and also gear mechanism for controlling the rotation of the drawing 55 mechanism of Fig. 2. Fig. 4, is a central longitudinal section through the wire rotating device of Fig. 1, showing the detail construction and arrangement thereof. Fig. 5, is a top or plan view of the wire rotating device with 60 its gear for permitting of the actuation thereof. Fig. 6, is a central longitudinal section through the drawing mechanism of the machine of Fig. 2; and Fig. 7, is a top or plan view of the same. 70

Referring to the drawings A, is a standard provided with a bearing *a*, set at an angle thereto and formed integral therewith.

B, is a reeling device provided with a rear spindle or journal *b*, detachably engaging the bearing *a*, of the standard *A*, and having mounted thereon a grooved pulley *b'*. This reeling device *B*, is provided with pegs or the like *b''*, extending from the face for supporting the wire in coiled form thereto and so as to 80 permit of the ready reeling off of the same therefrom.

c and *c'*, are standards to which are journaled pulleys *c''* and *c'''*.

D, is a wire rotating device provided with 85 end hollow journals *d* and *d'*, mounted in flanged bearing blocks *d''* and *d'''*, of standards *D'* and *D'''*, which are respectively provided at the top with lubricating receptacles *d''* and *d'''*, having vertical channels extending 90 to the journals *d* and *d'*. This device *D*, at one end thereof is provided with a gear wheel *d''*, which meshes with a gear-wheel *e*, mounted on the main driving shaft *E*, of the machine. This shaft is held to position at one portion 95 thereof, as illustrated in Fig. 1, in the standards *D'*, *D''* and *D'''*, and at the other portion, as illustrated in Fig. 2, in the standards *D''*, *D'''* and *D'''*.

On the left hand end of the journal *d*, of 100

the wire rotating device D, is mounted a grooved pulley d^9 , and engaging therewith is a cord or chain c^4 , which passes around the pulleys c^2 and c^3 , and also the pulley b' , of the reel B, for imparting rotary motion thereto. The pulley d^9 , has motion imparted thereto from the main driving shaft through the intervention of the gear wheels e and d^8 , as illustrated in Fig. 1.

10 F, is a steam jacketed tank or vat with a removable cover f .

f' is a U-shaped entrance nozzle in cross section extending through one of the side walls of the outer shell and the inner casing 15 of the tank or vat F, and in the opposite side wall thereof is provided a V-shaped exit nozzle f^2 . This tank is mounted on brackets f^3 and f^4 , secured respectively to the standards D^2 and D^3 .

20 The wire rotating device D, is provided with a surrounding casing d^{10} , having two series of grooved rolls d^{11} and d^{12} , suitably journaled to movable bearings d^{17} and d^{18} , provided in the walls of the casing d^{10} , and with pivotally 25 supported tightening devices d^{13} and d^{14} , controlled by means of swivel-connections d^{15} and d^{16} , for frictionally engaging and disengaging said series of grooved rolls d^{11} and d^{12} , to and from the drawn wire 10, in its travel 30 between the same.

In the rotation of the device D, by means of the gear-wheels d^8 and e , the wire 10 is revolved around and around and at the same time at required speed is drawn through the 35 machine in a manner to be presently more fully explained.

G, is a carding engine or machine of any suitable construction provided with a main driving shaft g , having a driving pulley g' , at 40 one end thereof, and adapted to be connected by means of a belt, not shown, with a driven wheel or pulley e' , mounted on the main driving shaft E, of the machine.

45 Adjacent to the clothing of the carding engine or machine G, is located a wiper or delivery roll g^2 , as clearly shown in Figs. 1 and 2, and arranged so as to present the fibrous material to the rotatable wire 10, drawn longitudinally in the path of crosswise delivery 50 of the material thereto and in such manner as to lay and wrap said material in spiral or similar form thereon, as will be presently more fully explained.

The standard D^5 , is provided with a flanged 55 tubular bearing block d^{19} , having a vertical channel d^{20} , extending through the same and in communication with a dish-shaped lubricating receptacle d^{21} .

h , is a funnel-shaped hollow spindle or 60 nozzle projecting through the bearing block d^{19} , which is made to taper to the opposite end secured into and extending through the base plate h^4 , of a whirler or flier-frame H, provided with a series of spindles h' , secured 65 into the same for the reception of bobbins or spools h^2 , for containing cord or thread.

It may be here remarked that the applied

fibrous material 11, from the carding engine G, to the constantly drawn and rotating wire 10, in passage through the nozzle h , will be 70 compacted thereto and present a smooth surface before reaching the whirler or flier frame H, for the reception of a binder 12, therefrom. This whirler or flier frame H, is provided with a grooved pulley h^3 , which is adapted for the 75 reception of a belt, not shown, for rotating the same from any suitable source of power so as to permit in the rotation of the wire 10, of the whirler H, laying by means of the bobbins or spools h^2 , a series of threads in regular 80 succession onto the covered wire so as to present a smooth surface and to constitute an efficient binder therefor.

I, is a wire drawing mechanism, comprising a tapering rotatable shell i , provided at both 85 ends with hollow journals i^1 and i^2 , engaging the flanged bearing blocks d^{22} and d^{23} , of the standards D^6 and D^7 , having lubricating receptacles d^{24} and d^{25} , provided with channels leading therefrom to the hollow journals of 90 the device I. At one end of the shell i , to the hollow journal i^2 , is rigidly mounted a gear wheel i^3 , and at the opposite tapering end thereof is mounted a disk i^4 , on the journal i^1 , which is secured by means of screws i^5 and i^6 , to the standard D^6 . This disk i^4 , is provided with a gear i^7 , which meshes with a gear i^8 , journaled to one of the side walls of the shell i .

i^9 , represents a series of similar gears occupying staggered positions and meshing with each other and mounted on cross shafts i^{12} , which are journaled to the respective side walls of the shell i . On the series of cross shafts i^{12} , are rigidly mounted two series of 105 grooved rolls i^{13} and i^{14} , adapted to frictionally contact with the covered and corded wire 10, in such manner that in the rotation of the device I, by means of the gear i^3 , thereof and its complementary meshing gear i^8 , mounted 110 on the main driving shaft E, the two series of rolls i^{13} and i^{14} , of the device I, by means of the series of gears i^7 , i^8 , and i^9 , in the direction of the arrows as shown in Fig. 6, are actuated 115 to cause the covered and corded wire 10, to be continuously drawn in a forward direction through the several appliances of the machine hereinbefore described. The hollow revoluble journal i^2 , of the wire drawing mechanism I, is extended at the right hand portion thereof 120 and to which is secured a double grooved pulley j , and a single grooved pulley j' . The latter pulley carries a nozzle or delivery tube J, with enlarged ends and with a contracted and curved body portion, as shown in Fig. 2, 125 for permitting of the delivery of the covered and corded conductor 10, drawn therethrough, onto a device to be hereinafter explained.

K, is a standard with an angular bearing k , to which is detachably secured a laying up 130 reel L, provided with pins or stays l , and with a spindle or journal l^2 , carrying a grooved pulley l^3 . The spindle or journal l^2 , engages the bearing k , of said standard K. m and m' ,

are standards provided with grooved pulleys m^2 and m^3 .

n , is a cross belt engaging the pulleys j and m^2 , and likewise the pulley j' , and passing around the pulley m^3 and pulley j^3 , of the reeling device L , for rotating the latter by means thereof from the main driving shaft by the gears e^3 and i^3 , as illustrated in Fig. 2.

The operation of the machine hereinbefore described is as follows:—The wire is drawn from the reel B , by means of the mechanism I , through the wire rotating device D , and between the two series of frictional rolls thereof to and through the bath of insulating material contained in the steam jacketed tank F , thence into the presence of the fibrous material delivered in regulated quantity from the carding engine G , and so that in the rotation of the wire drawn in the manner hereinbefore described, the fibrous material, such as cotton or the like, in spiral or other form will be incorporated with and wrapped around the more or less moist wire 10 , from the bath of insulating material and which is presented at the funnel-shaped end of the nozzle h , of the whirler or flier frame H , drawn therethrough and uniformly compacted to the wire prior to the laying onto the same in regular succession of the series of threads or cords from the flier frame or whirler H , for instance as illustrated in Fig. 2, and thence through the device I , and the respective hollow spindles thereof to and through the delivery nozzle or tube J , onto the laying up reel L , as will be readily understood from Figs. 1 and 2, of the drawings.

It may be here remarked that after the starting of the machine such as hereinbefore described, the fibrous material is applied continuously to the rotating insulated wire 10 , and as well the cord or thread to form the binder therefor and prior to the laying up of the same onto the reel for subsequent use, as an electric conductor. After the applying of the wire in coiled form onto the reeling device L , it may be withdrawn therefrom through a bath of insulating material to thoroughly saturate the same and to produce thereby an insulated electric conductor or from the reeling device L , the material may be subjected to a braiding or weaving operation to form an outer covering therefor, which it is desirable in some cases to provide such a conductor with, for outside work.

It will be manifestly obvious from the foregoing description that modifications may be made in respect to details or the particular arrangement of the machine of my invention for the aforesaid purposes, without departing from the spirit thereof; and hence I do not wish to be understood as limiting myself to the precise construction and arrangement of a plant as hereinbefore explained.

I am aware that telegraph cables have been provided in which successive layers of bitumen separated and maintained by spiral

bands of bituminized paper have been applied and consolidated by coils of bituminized twine or yarn, and the whole protected by an outer covering of metallic wire. Therefore, I lay no claim to any such construction for the production of a cable, for my invention differs therefrom in that it consists essentially in the mode of subjecting a wire to the operations hereinbefore described and to be hereininafter pointed out in the claims by the employment of suitable apparatus for the production thereof.

Having thus described the nature and objects of my invention, what I claim as new, and desire to secure by Letters Patent, is—

1. The herein described mode of producing an electric conductor, which consists in continuously rotating and drawing a wire through a bath of insulating material, feeding and while the coated wire is still moist applying and compacting cotton or the like under required tension and in regulated quantity to said continuously rotated and drawn wire and applying threads to said covered wire to form a binder therefor, substantially as and for the purposes set forth.

2. An apparatus for producing an electric conductor, comprising a reel adapted to contain wire, means controlled from a main driving shaft for rotating said wire, a jacketed appliance adapted to contain fluid insulating material, a carding engine adapted to present fibrous material in the path of the moving wire, a whirler or flier and a device connected therewith for compacting said material to said wire and said whirler or flier adapted to lay a cord or thread in regular sequence onto said covered wire, mechanism for drawing said wire and actuated by means of gearing from said driving shaft, a delivery nozzle or tube, a rotatable laying up reel, and means for actuating said moving members, substantially as and for the purposes set forth.

3. An apparatus for producing an electric conductor, comprising a rotatable reel adapted to support wire, a main driving shaft, means for actuating said reel and controlled from said shaft, a wire rotating device, a tank adapted to contain material for application to said wire and provided with entrance and exit nozzles of different forms, a carding engine with delivery appliances, a whirler or flier with a funnel-shaped nozzle for compacting fibrous material to said wire and prior to cording of the same by means of said flier or whirler, a wire drawing mechanism controlled by means connected with said driving shaft, a delivery nozzle and winding up reel, substantially as and for the purposes set forth.

In testimony whereof I have hereunto set my signature in the presence of two subscribing witnesses.

JOHN ROBINSON.

Witnesses:

THOMAS M. SMITH,
RICHARD C. MAXWELL.
